SLAGGING FLYASH

Frank G. Feesley, Jr., Larchmont, N. Y., assignor to Riley Stoker Corporation, Worcester, Mass., a corporation of Massachusetts

Application September 17, 1953, Serial No. 380,741

3 Claims. (Cl. 122—240)

This invention relates generally to melting dust-like materials and more particularly to a method and apparatus for performing such operations as reducing the fly ash collected in the back passes of a steam generating unit to a molten slag.

One of the outstanding problems encountered in the operation of large power plants is the disposal of the great quantities of flyash which are collected in the back passes and other parts of the steam generating unit. This flyash may be used for filling and reclaiming swamp areas and the like adjacent to the steam generating unit, but eventually these places for disposal become filled. If it then becomes necessary to cart the flyash away by truck, the cost of disposal goes up very greatly. If, however, the flyash can be removed from the hoppers and collectors of the steam generating unit and converted to a slag, its bulk is materially reduced, and, furthermore, it becomes in many cases a commercially saleable product. If at the same time that the flyash is reduced to a slag the carbon remaining in the flyash is converted to sensible heat, a very desirable situation exists. Slag in its hardened state has a very hard glass-like quality that is useful as a road bed material and has been used as a base material for manufacturing fibrous insulating material. Attempts in the past to slag this flyash have been unsuccessful for many reasons. First and foremost, it is not possible to reinject the flyash into the high temperature portion of the conventional furnace because of the danger of carryover into the back passes; that is to say, reinjection of flyash brings about a substantial loading of the furnace gases. The danger exists also of the flyash slagging in the boiler passes, in which cases it sticks to the boiler tubes and forms an insulating coat around them. Furthermore, in some furnaces there is no area which reaches a temperature sufficiently high to reduce the flyash to a slag. Attempts in the past to slag flyash in conventional furnaces have resulted in failures. Similar difficulties have been experienced in melting and agglomerating metallic dusts from mining operations and from metallurgical furnaces. The present invention obviates in a novel manner the difficulties experienced in the past in such operations as are set forth above.

It is therefore an outstanding object of the invention to provide a method and apparatus for melting dust-like materials.

Another object of the invention is the provision of a method to be used in conjunction with a conventional furnace for reducing flyash to a slag.

Still another object of the instant invention is the provision of an apparatus to be used in association with a conventional furnace for slagging flyash collected from the back passes of the steam generating unit with which it is to be used.

Still another object of the invention is the provision of a method for producing a zone of high temperature in association with a conventional furnace and introducing dusts therein for the slagging thereof.

A further object of the present invention is the provi-

2

sion of an auxiliary furnace to be used in conjunction with a conventional furnace for producing a zone of high temperature and introducing flyash therein.

Another object of the invention is the provision of an auxiliary furnace for slagging flyash, making use of high heat release burners.

Another object of the invention is the provision of an auxiliary furnace to be mounted in operative association with a conventional furnace, having high heat release burners associated therewith for producing a zone of high temperature followed by an oxidizing zone, and having means for introducing flyash for reducing it to a slag.

Although the novel features which are believed to be characteristic of this invention will be particularly pointed out in the claims appended hereto, the invention itself, as to its objects and advantages, the mode of its operation and manner of its organization may be better understood by referring to the following description taken in connection with the accompanying drawings forming a part thereof, in which:

Figure 1 is a vertical sectional view of a steam generating unit embodying the principles of the present invention,

Figure 2 is an elevational view partly in section of an apparatus for practicing the invention, and

Figure 3 is a plan view of the apparatus shown in Figure 2.

Like reference characters denote similar parts in the several figures of the drawings.

Referring first to Figure 1, which best shows the general features of the invention, a steam generating unit indicated by the reference numeral 10 is shown as comprising a furnace 11 and a boiler 12. The furnace 11 is of the water-cooled, slag-tap type and is made up of a forward wall 13, rear wall 14, and side walls 15, defining a combustion chamber 16. At the bottom of the combustion chamber 16 is situated a refractory slag bottom 17 of the usual type, having a means, not shown, for withdrawing molten slag from time to time. Mounted in the forward wall 13 of the furnace is a burner 18 for burning pulverized coal. The boiler 12 is made up in the usual manner of a steam-and-water drum 19 and a mud drum 20 joined by downcomer tubes 21. A large feeder tube 22 joins the mud drum 20 with a header 23 which overlies the top edge of the slag bottom 17 and which serves water wall tubes 24 which cover the inner surfaces of the walls 13, 14, and 15 for cooling the combustion chamber 16 and forming steam. Also included in the boiler system is a superheater 25 of the convection type. In the lower part of the back pass of the boiler 12 is a hopper 26 in which is collected cinder and flyash deposited therein. A cross-flow airheater 27 is mounted rearwardly and coextensive with the boiler 12 and is operatively connected in its lower portion with a cyclone type dust separator having a hopper 29 in which the dust is collected. Mounted rearwardly of the airheater 27 and generally coextensive therewith is an electrostatic precipitator 30 having a hopper 31 in the lower portion in which dust is collected. An induced draft fan 32 is mounted below the precipitator 30 and provides the draft for the entire furnace. An air duct 33 connects the airheater 27 to the burner 18 for supplying secondary air for combustion.

Mounted to the rear of the furnace 11 and generally coextensive with the lower portion thereof is a flyash slagging apparatus 34 having a burner portion 35 and a barrel 36. The barrel 36 has an elongated tubular vertical portion 37 and a short horizontal portion 38. A lower plane surface 39 is provided in the bottom portion of the horizontal portion 38 and is inclined toward the furnace, the furnace end thereof being on the usual level of slag

in the pool of slag 40 in the slag bottom 17. The upper horizontal surface 41 of the horizontal portion 38 is on a level considerably above any level of slag ever encountered in the pool 40.

Referring next to Figures 2 and 3 wherein are shown more detailed aspects of the flyash-sludging apparatus 34, it can be seen that the burner portion 35 of the apparatus is formed of refractory material so as to form a portion 42 which is more or less an extension of the barrel 36 and a reduced tubular portion 43 of considerably less a diameter than the barrel 36. The portions 42 and 43 are joined by a frusto-pyramidal portion 44 and the upper end of the portion 43 is closed by a generally pyramidal portion 45. The portions 42, 43, 44, and 45 have axes that lie on the axis of the barrel 36. Through the apex of the pyramidal portion 45 extends a nozzle 46 through which passes a mixture of flyash and air. In the central portion of each of the four sides of the pyramidal portion 45 is situated a high heat-release burner 47 through which passes a mixture of gas and air which originates in a manifold 48 serving high heat-release burners. The tubular portion 43, which is of square cross section, and the pyramidal portion 45 serve to define a small chamber 49. In the central portion of each of the four sides of the pyramidal portion 44 is situated an air nozzle 50 which surrounds the portions 42 and 44. Situated on each of the four sides of the portion 42 are two high heat release burners 52. The burners are situated in close side-by-side relationship on opposite sides of the longitudinal center line of the respective side of the portion 42. These burners are of the same type as the burner 47 and may be of a special type wherein a high heat release is obtained by recirculating a portion of the combustion gases to adjacent the ignition point of the burner, whereby the ignition of incoming gases is facilitated and tremendous amounts of energy are released in a very small volume. These burners receive their gas from gas manifolds 53 and 54 which entirely encircle the apparatus. The burners 52 receive their air from the air plenum chamber 51. The burners 47 are inclined inwardly and downwardly and meet on the axis of the nozzle 46 at a portion thereof somewhat centrally of the small chamber 49. The burners 50 are also inclined downwardly and inwardly and meet on the axis at a point somewhat downwardly of the burners 52. The air ports 50 and the burners 52 fire, of course, into the large chamber 55 defined by the barrel 36, the portion 42, and the pyramidal portion 44.

Returning to Figure 1 once more it is to be noted that a forced draft fan 56 applies air to an ejector 57 which discharges into a duct 58. The duct 58 is connected in series with the bottom portions of the hoppers 31, 29, and 26 and connects finally with the nozzles 46. A gas pipe 59 connects to the manifold 48 serving the burners 47 and to the gas manifolds 53 and 54 which serve the burners 52. Also a duct 60 branches off the main air duct 33 and serves the burners 47 and the air plenum chamber 51.

The operation of the invention will now be understood in view of the above description. To begin with, the furnace 11 and the boiler 12 are operated in the usual manner with the burner 18 discharging into the combustion chamber 16 and the hot gases rising and passing over the superheater surfaces and the surfaces of the down-comer tubes 21 and transferring heat to the water and steam contained therein. The water wall tubes 24, of course absorb heat by radiation. The hot gases, after going through the back pass of the boiler, pass through the airheater where incoming air is heated before passage through the duct 33 to serve the burner 18. The gases after leaving the airheater 27 enter the cyclone separator 28 where a certain amount of the dust and cinders is removed. The gases then enter the electrostatic precipitator 30 and any remaining dust and flyash is removed and deposited in the hopper 31. The induced draft fan 32, of course, projects the gases upwardly through the pre-

cipitator 30 where they eventually travel into the stack, not shown. The extreme heat in the combustion chamber 16 causes a certain amount of the ash remaining after combustion to reach the slagging temperature in which case the slag passes downwardly through the chamber into the slag bottom 17 forming the pool 40. Slag is also deposited on the water walls and on the tubes over the chamber and drip and run downwardly into the pool 40. When the level of the slag pool 40 reaches a certain depth, some of the slag is removed. At the same time that the furnace is operating in the normal manner, hot gases and slag are received from the flyash sludging apparatus 34. To begin with, air is supplied to the burners 47 and the air plenum chamber 51 through the duct 60 which taps air from the duct 33. Gas from the pipe 59 mixes with the air in the burners 47 and with air in the burners 52 forming a combustion mixture which is burned in these burners with an extremely high heat release, as has been explained. At the same time the fan 56 discharging air through the ejector 57 picks up flyash, cinders and dust from the hoppers 31, 29, and 26. The air carrying the flyash along the duct 58 and permitting it to be mixed and discharged through the nozzle 46 and into the small chamber 49. In the chamber 49, then, exists a mixture of the extremely hot gases of combustion originating in the burners 47 and the air and flyash originating in the nozzle 46. Preferably, the gases in the chamber 49 contain little or no excess air; this is accomplished by supplying the bare minimum for combustion at the burners 47 and the minimum for carrying the flyash to the nozzle 46. In this way, the temperature in the chamber 49 can be very high. Discharging into the larger chamber 56 are heated air from the nozzles 50 and very hot gases of combustion from the burners 52. By the time the flyash particles arrive in the barrel 36 they will have been raised to a very high temperature. This high temperature along with the presence of excess air will cause the carbon to be burned out of the particles and the particles to be melted to slag. The slag will fall onto the surface 38 and will run into the slag bottom 17 and the slag pool 40. The gases of combustion will also pass downwardly through the barrel 36 into the short horizontal portion 38, will impinge on the pool of slag, and will rise upwardly through the combustion chamber 16, supplementing the flame and hot gases originating in the burner 18.

In a typical installation the burner 47 will use 177 pounds per hour of natural gas and 2,970 pounds per hour of air at 670 degrees F. and 5 inches of water pressure. This will give 10% excess air and a mixture pressure of approximately 4 inches of water. The nozzle 46 will receive a total of about 4,000 pounds per hour of flyash and 2,000 pounds per hour of air at 670 degrees F. A mixture of flyash and air will be discharged through the nozzles at a velocity of about 38 feet per second. This means that the mixture of hot combustion gases originating in the burners 47 and flyash and air originating in the nozzle 46 will leave the small chamber 49 at a velocity of about 40 feet per second, and a temperature of 2,000 degrees F. The air ports 50 will receive in all approximately 12,860 pounds per hour of air at 670 degrees F. and 5 inches of water pressure and will leave the nozzles 50 at about 190 feet per second. The high heat release burners 52 will use 240 pounds per hour of natural gas and 3,760 pounds per hour of air at 607 degrees F. The maximum velocity of the mixtures of gases and flyash traveling through the barrel 36 will be about 84 feet per second.

While certain novel features of the invention have been shown and described and are pointed out in the annexed claims, it will be understood that various omissions, substitutions and changes in the forms and details of the device illustrated and in its operation may be made by those skilled in the art without departing from the spirit 75 of the invention.

Having thus described my invention, what I claim as new and desire to secure by Letters Patent is:

1. Apparatus for use in slagging flyash comprising a main combustion chamber having a gas off-take at its upper end and a slag bottom at its lower end, pulverized coal burners mounted adjacent the bottom to provide for most of the combustion which takes place in the chamber, an auxiliary chamber adjacent the said bottom, the chamber being of vertically-elongated form, means for introducing a stream of fly-ash downwardly into the upper part of the auxiliary chamber, high-heat-release burners surrounding the auxiliary chamber and introducing hot gases into the stream of flyash to produce turbulence, the mixture of gases and flyash reaching a temperature above the fusion temperature of flyash within the auxiliary chamber.

2. Apparatus for use in slagging flyash comprising a main combustion chamber having a gas off-take at its upper end and a slag-tap bottom at its lower end, pulverized coal burners mounted adjacent the bottom to provide for the larger part of the combustion which takes place in the chamber, an auxiliary chamber having an opening into the main combustion chamber adjacent the said bottom, the chamber being of elongated tubular form with its centerline arranged vertically, means for introducing a stream of flyash downwardly into the upper part of the auxiliary chamber, high heat-release burners surrounding the centerline of the auxiliary chamber and introducing hot gases into the stream of flyash to produce turbulence, the mixture of gases and flyash reaching a temperature above the fusion temperature of flyash within the auxiliary chamber.

3. Apparatus for use in slagging flyash comprising a main combustion chamber having a gas off-take at its upper end and a slag-tap bottom at its lower end, pulverized coal burners mounted adjacent the bottom to provide for the larger part of the combustion which takes place in the chamber, flyash collector means arranged to remove flyash from the combustion gases originating in the chamber, an auxiliary chamber having an opening into the main combustion chamber adjacent the said bottom, the chamber being of elongated tubular form with its centerline arranged vertically, means for introducing a stream of flyash from the collector means downwardly into the upper part of the auxiliary chamber, high heat-release gas burners surrounding the centerline of the auxiliary chamber and introducing hot gases into the stream of flyash to produce turbulence, and means introducing sufficient air into the chamber to burn both the gas and the residual carbon in the flyash, the mixture of gases and flyash reaching a temperature above the fusion temperature of flyash within the auxiliary chamber.
